OTTO R. ROENIUS AND WILLIAM F. GLEUE, OF GRAND RAPIDS, MICHIGAN.

MEANS FOR FACILITATING THE MARKING OF BUTTON POSITIONS ON SHOES.

1,112,096.

Specification of Letters Patent. Patented Sept. 29, 1914.

Application filed January 31, 1913. Serial No. 745,522.

To all whom it may concern:

Be it known that we, OTTO R. ROENIUS, a citizen of the United States, and WILLIAM F. GLEUE, a subject of the Emperor of

5 Germany, residing at Grand Rapids, in the county of Wood and State of Wisconsin, have invented a new and useful Means for Facilitating the Marking of Button Positions on Shoes, of which the following is a

10 specification.

This invention has reference to improvements in means for facilitating the marking of button positions on shoes, and its object is to provide a device upon which a 15 shoe may be placed for properly positioning the points where buttons are to be applied, the device of the present invention being designed for use in connection with button shoes.

20 In the manufacture of button shoes the buttons are applied by a machine while the buttonholes are made by another machine and their positions are regulated by an operator so that oftentimes there is more or 25 less discrepancy of position with respect to the buttons and the buttonholes, and when a shoe so made is applied to the foot of the wearer unsightly wrinkles are often produced due to the lack of matching between 30 the buttons and the buttonholes. Again, it is often necessary to change the positions of the buttons, and this is also productive of unsightly conditions.

By the present invention the buttonhole 35 fly can be correctly located upon the small quarter and the position which the buttons are to occupy is readily indicated upon the small quarter even though the buttonholes be irregularly spaced. For this purpose the 40 invention comprises a form having a foot end and a leg portion, both of which need only generally conform to the shape of the human foot and adjacent portion of the human leg, since the foot portion is designed 45 simply as a positioning member to be inserted in the foot portion of the shoe to be treated, while the leg portion is designed as a support for the button and buttonhole flies, so that the buttonhole fly may 50 be overlapped on the small quarter to an appropriate extent, and then have a smooth support permitting the marking of the positions of the buttonholes upon the small quarter by means of a lead pencil or 55 other suitable marking tool, whereby the buttons may be located accurately with re-

lation to the buttonholes even though the latter be quite unevenly spaced, and unsightly wrinkles and ill fitting shoe tops are avoided.

60 By the use of the present invention button shoes may be furnished to the dealers with but a very few of the buttons, say, those at the instep only, in position, while the remainder of the buttons may be omitted to 65 be applied when the shoe is fitted to the customer, whereupon the shoe is placed upon the holder of the present invention and the buttonhole fly may be brought into non-wrinkling relation to the small quarter and 70 the positioning of the buttons accurately located through the buttonholes, such buttons being applied by the aid of the button applying machines usually present in shoe stores.

75 The invention will be best understood from a consideration of the following detailed description taken in connection with the accompanying drawings forming a part of this specification with the further understanding that while the drawings show a 80 practical embodiment of the invention, the latter is not confined to any strict conformity with the showing of the drawings, but may be changed and modified so long as 85 such changes and modifications mark no material departure from the salient features of the invention.

In the drawings:—Figure 1 is a plan view of the structure of the present invention 90 with a shoe applied thereto, the latter being shown partly in full lines and partly in dotted lines. Fig. 2 is a section on the line 2—2 of Fig. 1, but drawn to a larger scale, with distant parts omitted. Fig. 3 is a section on the line 3—3 of Fig. 1 but drawn to a larger scale. Fig. 4 is a section on the line 4—4 of Fig. 3. Fig. 5 is a perspective view of the form removed from its support.

95 Referring to the drawings, there is shown a form 1 corresponding in shape to a shoe tree having an instep portion 2 corresponding in curvature to the natural curve of the instep, and the form 1 has a foot portion 3 of shorter length and otherwise of 100 smaller size than the foot receiving portion of a shoe adapted to the form, and said form also has a leg portion 4, which latter may in some degree conform to the shape of the human leg above the ankle to 105 a point somewhat higher than is reached by a shoe indicated in the drawing at 5. The

leg portion 4 may be thinner than the corresponding portion of the human leg and may, in fact, be relatively flat or it may conform quite closely to the shape of the human leg 5 for a distance above the ankle. In Fig. 2 the leg 4 is shown as a relatively flat ellipse in cross section, but it is to be understood that the showing of the drawings in this respect is more or less indicative, and in 10 practice it is customary to provide two or three or more forms of different sizes with each outfit.

That end 6 of the form 1 remote from the foot 3 is shown in the drawings as quite 15 flat, and in cross section defining a rather elongated rectangle. This end 6 is provided at a short distance from its extremity with oppositely located recesses 7, one being on one face of the end 6 and the other in the 20 other face thereof, and these recesses 7 are approached by grooves 8 opening at the extremity of the portion 6. The flattened part 6 of the form is designed for introduction into a socket 9 produced in a holder 25 10 shown in the drawings as formed of two nested U-shaped flat metal members 11, 12, riveted together with the adjacent yoke portions spaced apart. The yoke portion of the member 11 has a perforation 13 there- 30 through normally traversed by a block 14 on one end of a leaf spring 15, the block being rounded on the free face so as to lodge in one of the recesses 7. The member 11 has its side portions or legs formed with ter- 35 minal flanges 16 by means of which it may be fastened on a table or counter 17 or other suitable support. The holding structure for the form 1 may be otherwise arranged than indicated in the drawings, so as to be fas- 40 tened to some other supporting structure than the table 17 or the like, the shape of the holding member being designed to ac- 45 commodate it to the different positions in which it may be secured.

45 With a structure such as described the form 1 is readily introducible into the socket 9 and will engage and push the block 14 out of the way until the recess 7 then uppermost or toward the block 14 is brought 50 into coincidence therewith, when the reac- 55 tion of the spring 15 will cause the block 14 to seat in said recess, thus holding the form 1 against accidental displacement under conditions of use. The form is reversi- 60 ble to accommodate it to right and left shoes and by supplying forms having dif- 65 ferent leg portions and differing in the foot part, all the different sizes of shoes may be readily accommodated, such forms being so arranged that a shoe may be slipped onto or off from the same very easily, while the form is wide enough to serve as a rest for the shoe while marking the same in the manner to be described.

65 The shoe buying public demands a per-

fect fitting button shoe, and it is therefore necessary to make the shoes fit well, which can only be done by having the buttons put on perfectly. Moreover, such an arrangement of the buttons gives an even strain on 70 each button so that there is no liability of tearing out the button holes or tearing off the buttons.

Under the conditions of manufacture no 75 shoes as now manufactured have the buttons fastened on in the proper relation to the buttonholes, since the manufacturer either cannot or does not mark the spaces for the buttons through the buttonholes, but simply sews the buttons on by a machine 80 which places the buttons in such spacing as provided for by the set of the machine. The buttons are placed on very regularly, that is, they are spaced equally apart but the buttonholes are each made separately, 85 and the spacing depends upon the operator, so that such spacing is not accurate and no matter how careful the operator may be the buttonholes and buttons can never match. The present invention avoids this difficulty 90 by providing means whereby the spaces for the buttons may be marked through the buttonholes and the buttons may then be fastened at the marked places so as to conform exactly with the spacing of the buttonholes. Moreover, it often becomes necessary to reset the buttons either forwardly 95 or backwardly to fit the foot of a customer, whereupon the buttons having been removed the shoe may be placed upon the form of 100 the present invention, the flies smoothed out and the places for the buttons marked through the buttonholes, and then the buttons may be so placed as to avoid any liability of wrinkling when the shoe is placed 105 upon the foot of the customer and buttoned up.

Because of the present invention the dealer may demand of the manufacturer 110 that the shoes be supplied with only those buttons which fit over the instep and the balance of the buttons toward the top omitted whether the shoes be of regular heights or provided with high tops, while the omitted buttons may be separately supplied. 115 Again, where already attached buttons must be removed for fitting, the needle holes are 120 objectionable, and, furthermore, weaken the shoe. This is remedied by the present invention since the major portion of the buttons need not be applied until the shoe is fitted to the customer and, moreover, fitted in a manner avoiding wrinkling.

By making the form alike on both sides 125 it becomes interchangeably right and left and by providing two or more forms provision is made for all sizes of shoes.

The supporting device for the form shown in the drawings is of simple and convenient construction, but this does not preclude 130

the use of other supporting means capable of sustaining at one time as many forms as desired where economy of room is not material.

5. A distinguishing feature of the present invention is that it provides a support for a button shoe which permits the proper positioning of the buttonhole fly with respect to the small quarter, so that the positions of the buttons may be marked thereon in proper matching relation to the buttonholes and when the buttons are applied in the marked positions they will conform to the positions of the buttonholes in a manner to 10 avoid any wrinkling due to imperfect relation of the buttons and buttonholes whether such imperfect relation be due to the conditions of manufacture or to any other cause, and, furthermore, the present 15 invention permits the supplying of shoes to the dealer with but a minimum number of buttons already in place so that the remainder of the buttons may be afterward applied with the assurance that the shoe will 20 fit the customer without wrinkling of the flies or unequal strain upon the buttons or 25 buttonholes.

Trade conditions demand that all buttons applied by the dealer be fastened by wire, 30 while the shoes as supplied by the manufacturer have the buttons fastened with thread. In a very large percentage of cases the first three to five buttons which hold the shoe over the instep will fit so that re- 35 setting of buttons usually applies to those higher up. With the present invention these first three to five buttons may be fastened with wire which hold the buttons in their proper places much better than thread, 40 so that there is no liability of these few buttons pulling loose, as is often the case where they are fastened with thread, and consequently there need be no uncertainty about the fit of a shoe. The present invention pro- 45 vides a means whereby the remaining buttons may be accurately placed and may then be secured by wire in the usual way without having the small quarter of the shoe weakened or rendered unsightly by the needle 50 holes caused by securing the upper buttons by thread.

What is claimed is:—

1. A device for the purpose described, comprising a form having a leg portion of greater width and less thickness than the like parts of the human leg of a size corresponding to the form, said leg portion being of flattened elliptical cross-section, and a foot entering portion of smaller size 55 than the foot-receiving portion of a shoe otherwise adapted to the form, with said foot-entering portion provided with an instep part corresponding in curvature to the natural curve of the instep, the leg portion 60 of the form being shaped to provide a solid 65

or unbroken support for the short quarter and buttonhole fly of a shoe applied to the form with the buttonhole fly overlapping the short quarter.

2. A device for the purpose described, 70 comprising a form alike on both faces and having at one end a shoe entering portion and at the other end a flat portion with the intermediate part of flat elliptical cross-section, and a holder provided with a latch member and shaped to receive the flattened 75 end of the form, said flattened end of the form being shaped on each face to receive the latch member.

3. A device for the purpose described, 80 comprising a form having a shoe entering part and a shank part, the shank part terminating at the end remote from the shoe entering part in a flat portion having recesses on opposite sides and grooves extending 85 from the end of the flat portion to the recesses, and a holder for receiving the flattened end of the form with either face of the form uppermost and provided with a yieldable latch member in position to engage 90 in a respective recess.

4. A device for the purpose described, comprising a form having a shoe entering part and a leg portion, the latter being relatively flat and of elliptical cross-section with 95 the shorter axis less, and the longer axis greater than like parts of a human leg of a size corresponding to the form, and where overlaid by the buttonhole fly and short quarter of a shoe applied to the form being 100 solid or unbroken to constitute a support for the named parts of the shoe during the marking operation.

5. A device for the purpose described, comprising a form with one end shaped to 105 enter the foot receiving part of a button shoe and with a leg portion longer than the leg receiving part of the shoe to project beyond the top of the upper of the shoe, the leg portion where corresponding to the 110 upper of the shoe when applied being in cross-section in the shape of a flattened ellipse of greater length and less thickness than like parts of a human leg of a size corresponding to the form, and that portion 115 of the form remote from the foot entering portion being flat and of substantially rectangular cross-section.

6. A device for the purpose described, comprising a form with one end shaped to 120 enter the foot receiving part of a button shoe and with a leg portion longer than the leg receiving part of the shoe to project beyond the top of the upper of the shoe, the leg portion where corresponding to the upper of the shoe when applied being in cross section in the shape of a flattened ellipse of greater length and less thickness than like 125 parts of a human leg of a size corresponding to the form, and that portion of the form 130

remote from the foot entering portion being flat and of substantially rectangular cross section, said device being also provided with a socket member shaped to receive the flat 5 end of the form remote from the foot entering part thereof.

In testimony, that we claim the foregoing

as our own, we have hereto affixed our signatures in the presence of two witnesses.

Correction in Letters Patent No. 1,112,096.

It is hereby certified that in the grant and in the heading to the printed specification of Letters Patent No. 1,112,096, granted September 29, 1914, upon the application of Otto R. Roenius and William F. Gleue, for an improvement in "Means for Facilitating the Marking of Button Positions on Shoes," the residence of the patentees was erroneously given as "Grand Rapids, Michigan," whereas said residence should have been given as *Grand Rapids, Wisconsin*; and that the said Letters Patent should be read with this correction therein that the same may conform to the record of the case in the Patent Office.

Signed and sealed this 20th day of October, A. D., 1914.

[SEAL.]

J. T. NEWTON,

Acting Commissioner of Patents.
